UNITED STATES PATENT OFFICE.

WILLIAM APPLETON, OF ALBANY, NEW YORK.

IMPROVEMENT IN MALT HOUSES OR KILNS.

Specification forming part of Letters Patent No. 21,117, dated November 19, 1867.

To all whom it may concern:

Be it known that I, WILLIAM APPLETON, of the city and county of Albany, in the State of New York, have invented a new and useful Improvement in Malt Houses or Kilns, of which the following is a full, clear, and exact description, reference being had to the accompanying drawings, forming part of this specification, and in which—

Figure 1 represents a longitudinal sectional elevation of a malt house or kiln constructed according to my improvement; Fig. 2, a transverse section through the line $x x$ in Fig. 1, and Fig. 3 an end elevation of the same.

Similar letters of reference indicate corresponding parts.

In malting as heretofore practiced it has been customary to admit air to and regulate the temperature of the steeped barley or room in which it is spread to heat and germinate by opening more or less windows in the sides of said room. This method involves frequent adjustment of such windows, according to the temperature or condition of the external atmosphere, and unless great particularity is observed, which necessitates great loss of time and labor, an undue exposure takes place that damages the grain or seriously interferes with the proper malting of the barley.

The object of my invention is to remedy this defect; and the nature of my invention consists in a novel arrangement of air openings and flues, whereby a constant supply of fresh air is or may be made to pass in a gentle current over the malt-floor by suction or draft, as induced by communication with the malt-kiln fire used in drying; and said invention further consists, in combination with the same, in an arrangement of other flues opening to the external atmosphere and conducting air above and below the kiln-fire, for, under certain conditions or at intervals, better regulating the strength of the current above referred to and temperature of the heating-chamber. By this my improvement the malting process is rendered more equable as regards the regulation of temperature, much labor and particularity dispensed with, and less exposure induced to sudden or violent and injurious changes of wind and weather.

Referring to the accompanying drawings, A, B, and C represent the floors of a malt house or kiln, the upper floor, A, say, serving

to store the barley before malting, and from which it is fed to the steeping-vessel D, to be passed from thence to the malting-floor C, the middle floor, B, answering to store the dried malt.

E are the windows to the chamber C, the same usually serving the purpose both of light and of regulating the temperature of said room and grain contained therein; but in this my improvement they are only necessary for lighting purposes, and may be kept closed.

To properly ventilate this chamber by admitting a constant and gentle current of fresh air to pass over the malt-floor, and so prevent "cutting of the roots of the grain" while germinating, I connect either heating-chamber F of the kiln proper by a tube or flue, G, with the malting floor or chamber C, and establish an opening or flue, H, (any number, according to the number of drying chambers or kilns proper,) at the opposite ends of said chamber C, whereby the fire in or heat of the chamber F induces a gentle and direct current of air from the outside over the malt-floor, which serves effectually to equalize or control the temperature, valves or dampers, if necessary, being furnished the flues G and H. In this way the kiln-fire used in drying may be made to control the temperature of the grain on the malt-floor, and of which fire, I is the hearth; J, the drying table or surface, furnished with feed and delivery communications K L; and M, the usual or any suitable shaft for carrying off the gases and vapor generated in drying.

The heating-chamber F is or may be further provided with a check-flue, S, preferably opposite the flue G, to prevent in very cold weather the too sudden introduction of cold air on or to the grain on the malt-floor and serving to reduce the strength of the kiln-fire; also, for the further introduction of air, should the same be required to modify or effect the current passing through the malt-house and through the flues G and S, a covered air box or flue, N, is arranged to conduct air from the outside atmosphere to and through, from below, the fire of the kiln proper. These flues S and N should also be provided with regulators or dampers. This latter flue, N, will likewise answer to supply air to the fire to effect or assist combustion. Of course one, two, or more kilns proper may be worked side by side in the one malt-house, the same being furnished with flues, as described.

What is here claimed, and desired to be secured by Letters Patent, is—

1. The induction of a current or currents of air over the malt-floor by means of draft pipes or tubes G, connecting said floor or chamber with the heating-chamber of the kiln, and in drying the malt, substantially as and for the purposes specified.

2. The combination of the flue S with the flue G to the malt-floor C, and heating-cham-

ber F, for operation together as herein specified.

3. The flue N, in combination with the heating-chamber F, malt-floor C, and flues G and S, for action in concert as specified.

WM. APPLETON.
